UNITED STATES PATENT OFFICE

2,399,006

MACHINE FOR DRAFTING FIBROUS MATERIALS

Geoffrey Dakin, Didsbury, Manchester 20, England, assignor to The British Cotton Industry Research Association, Manchester, England, a British association

Application March 27, 1943, Serial No. 480,728
In Great Britain April 18, 1943

4 Claims. (Cl. 19—131)

The present invention relates to improvements in the arrangements for drafting fibrous materials in spinning frames and similar machines, such as speed frames for cotton, in which an endless band, or apron as it is usually called, is used to assist in the conveyance and control of fibres during their passage between a rearward and a forward pair of rollers which constitute or form part of a drafting system.

It is usual in arrangements of this kind for the apron to co-operate either with a second apron or with a roller or rollers, or with fixed or free plates.

In my invention, for the purpose of controlling the fibres during drafting, I make use of a member which though it does not rotate progressively as the material is transmitted, possesses rotational and translational mobility of such kind and degree that not only is transmission perfectly satisfactory, but the control of the fibre is so effective that the uniformity of the drafted product is greater than can be obtained with ordinary roller systems, and high drafts are practicable.

In applying my invention I should arrange the apron below the material and the control member above it. The apron might be arranged in known fashion such as is adopted in double apron systems or those in which a roller or rollers co-operate with a single apron. My control member would rest on the apron (or rather on the material carried on the apron) and in order to prevent it from being carried forward by the apron, I might make its length rather greater than the width of the apron and constrain the projecting ends against suitable stops. Thus if the apron were carried in a cradle, I might provide slots in the side plates of the cradle, these plates being suitably extended above the plane of the operative surface of the apron; or if the aprons passed round nose-pieces formed on a rod extending over several units of the machine, I might provide pairs of posts in the rod.

The control member would have its lower or operative face smoothly finished and shaped rearwardly to provide a smooth lead-in for the fibres coming from the rearward pair of rollers. The part of this face resting on the material is plane.

According to my invention, I arrange the constraints of the control member so that it may perform such small rotational and translational motions as are necessary for it to accommodate itself to the irregular action of the stream of fibres. A preferred method of constraint com-

prises the provision on the ends of the control member of shaped edges which bear against constraining members (such as those of the kind previously mentioned) whose plane of action is normal or nearly normal to the plane of the operative surface of the apron. These edges define an axis round which the control member may pivot. I locate this axis in or near the plane of the operative surface of the apron, its precise position depending upon a number of factors such as the character of the material to be processed, or the distance apart of the lines of contact with the material. In general I prefer to locate the axis slightly forward of the point at which the material enters between the control member and the apron (Figs. 1, 3 and 4). Additional mobility is provided by the possibility of the slipping of the edges over their constraining members, such slipping affording relief for example when an exceptionally thick portion of the material is passing. In general the motion of the control member will be a combination of rotation and such translation.

The means for carrying the invention into practice are hereafter described in detail and with reference to the accompanying drawings, wherein:

Fig. 1 shows a control member and a supported driven apron and other details.

Fig. 2 is a perspective view of the control member seen in Fig. 1.

Fig. 3 is a view similar to Fig. 1 but with a modified form of cradle; the constraining members in this case are separate from the cradle and are shown in Figs. 4 and 5.

Fig. 4 is a view partly in section showing three lines of rollers and a control member similar to that shown at Fig. 2.

Fig. 5 is a plan view of Fig. 4.

Figs. 1 to 5 illustrate generally the application of my invention to a ring spinning frame for cotton, but it will be understood that the improvements may be applied to other machines in which fibrous materials are drafted, including those in which a total draft is distributed between successive drafting zones.

Figs. 1 and 3 illustrate devices in which different means of constraining the control member shown in Fig. 2 are used, these devices being applied to a spinning frame of the "three-line" type (i. e. having three pairs of rollers, back, intermediate, and front) after the manner shown in Figs. 4 and 5.

The Figs. 4 and 5 relate specifically to the application of the control member illustrated

in Fig. 2 and constrained by stops independent of the cradle.

In Figs. 1, 3, 4 and 5, the rollers 1 and 2 serve to drive the apron 3, which passes round the lower roller 1 and between said two rollers. In this particular example, these rollers 1 and 2 take the place of the ordinary intermediate rollers, but in accordance with known practice the boss of the operative portion of roller 1 is knurled or has saw-teeth cut upon it (as shown) to give a better grip on the apron 3. The roller 1 is positively driven in the ordinary manner so as to give a suitable draft, in general small, relative to the back rollers 4 and 5. I preferably provide roller 2 with a loose boss to obviate stoppage of the said roller 2 which is liable to occur owing to the presence of the apron between the rollers 1 and 2. To position the apron 3 I can with advantage make use of a cradle consisting of side-plates 6 rigidly interconnected as by stays 6^x (see Figs. 4 and 5). The side-plate 6 carry a transverse nose-piece 7 over part of the surface of which passes the front bend of the apron 3. This nose-piece 7 has end-projections 8 fitting into slots in the interconnected side-plates 6. Integral with the nose-piece 7 is a smooth-faced platform 9 which serves to support the apron 3 against the weight of the control member 10.

The rearward under portions of the side-plates 6 are shaped so that the axles of roller 1 may fit rotatably thereto, and upward extensions 11 of the side-plates 6 serve to locate the side-plates 6 and consequently the cradle by the contact therewith of the axles 12 of the rollers 2.

One form of application of the control member 10 is shown in Fig. 1, and the control member separately in perspective in Fig. 2. It is provided with end-pieces or lugs 13 which serve to keep it in position on the apron 3 by engagement of said end-pieces or lugs 13 against the edges of upward horns or extensions 14 of the side-plates 6. The rearward edge of the control member 10 is rounded off to provide a smooth lead-in for the textile fibres. It is preferably rounded off at all four longitudinal edges.

The preferred form of application of the control member 10 is shown in Figs. 4 and 5, the said control member being held independently of the cradles by the cap-nebs 15. These known cap-nebs 15 are fixed to supporting stems or fingers in the frame, in similar manner to those holding the roller 2 and upper front roller 16. As illustrated by Fig. 2, the lugs or end-pieces 13 of the control member 10 have plane faces inclined at an acute angle to the plane face which rests on the apron 3. Thus the control member 10 has power of limited rotational motion and is capable of rising and falling.

In Fig. 5 there is shown two cradles fixed about the roller 1 independently of each other.

In Fig. 4 the weighting of the roller 2 is shown as being effected by a saddle 17 and hook 18 which is weighted, such arrangement acting on a well-known principle and serves to weight the roller 2 and the top front roller 16.

It will be understood that the precise details as to the devices for carrying out my invention is susceptible of some constructional variation according to the particular type of fibre drafting machine to which they are applied.

I declare that what I claim is:

1. In a spinning machine for subjecting fibrous materials to the process of drafting, a device for controlling the fibres, comprising rearward and

forward pairs of drafting rollers, a conveying apron arranged to support the fibrous material in the path of travel of the fibrous material from one pair of rollers to the other, a loose control member having a plane lower face whereby it rests on the fibrous material on said conveying apron, said control member having end-pieces shaped to provide collinear pivoting edges whose common axis of pivoting lies approximately in the plane of the said lower face, and stops disposed in position to engage said pivoting edges thereby to constrain the forward motion of the control member while permitting the pivoting edges to slide in a plane approximately normal to the plane of the operative surface of the conveying apron, said pivoting edges being maintained in constant contact with the abutments in all pivotal movements of the control member and in vertical sliding movements thereof.

2. In a spinning machine for subjecting fibrous materials to the process of drafting, a device for controlling the fibres, comprising rearward and forward pairs of drafting rollers, a conveying apron arranged to support the fibrous material in the path of travel of the fibrous material from one pair of rollers to the other, a loose control member having a plane lower face whereby it rests on the fibrous material on said conveying apron, said control member having end-pieces shaped to provide collinear pivoting edges whose common axis of pivoting lies approximately in the plane of the said lower face and across its rear portion, and stops disposed in position to engage said pivoting edges thereby to constrain the forward motion of the control member while permitting the pivoting edges to slide in a plane approximately normal to the plane of the operative surface of the conveying apron, said pivoting edges being maintained in constant contact with the abutments in all pivotal movements of the control member and in vertical sliding movements thereof.

3. In a spinning machine for subjecting fibrous materials to the process of drafting, a device for controlling the fibres, comprising rearward and forward pairs of drafting rollers, an endless revolvable apron arranged to support the fibrous material in the path of travel of the fibrous material from one pair of rollers to the other, a control member resting loosely upon and coacting with said apron, said control member having a plane operative face and rounded lead-in and delivery edges and end lugs shaped to provide collinear pivoting edges whose common axis of pivoting lies approximately in the plane of said plane operative face and across its rear portion, abutments disposed to engage said pivoting edges thereby to constrain the forward motion of the control member while permitting sliding of the said pivoting edges in a plane approximately normal to the operative surface of the apron, said pivoting edges being maintained in constant contact with the abutments in all pivotal movements of the control member and in vertical sliding movements thereof.

4. In a spinning machine for subjecting fibrous materials to the process of drafting, a device for controlling the fibres, comprising rearward and forward pairs of drafting rollers, an endless revolvable apron arranged to support the fibrous material in the path of travel of the fibrous material from one pair of rollers to the other, a control member resting loosely upon and coacting with said apron, said control member having a plane operative face and rounded lead-in and

delivery edges and end lugs shaped to provide collinear pivoting edges whose common axis of pivoting lies approximately in the plane of said plane operative face, abutments disposed to engage said pivoting edges thereby to constrain the forward motion of the control member while permitting sliding of the said pivoting edges in a

plane approximately normal to the operative surface of the apron, said pivoting edges being maintained in constant contact with the abutments in all pivotal movements of the control member and in vertical sliding movements thereof.

GEOFFREY DAKIN.
